UNITED STATES PATENT OFFICE.

ROBERT THOMAS POWERS, OF OXFORD, MASSACHUSETTS.

LUG STRAP.

1,406,487.

Specification of Letters Patent. Patented Feb. 14, 1922.

Application filed April 8, 1920. Serial No. 372,201.

To all whom it may concern:

Be it known that I, ROBERT T. POWERS, a citizen of the United States, residing at Oxford, in the county of Worcester and State 5 of Massachusetts, have invented certain new and useful Improvements in Lug Straps, of which the following is a specification.

My invention relates to new and useful improvements in weaving machinery, and 10 more particularly to lug straps used in connection with the same, the primary object of the invention being to provide means to preclude wear imposed upon the lug strap by the picker arm operating therethrough.

Another important object of the invention 15 is to provide the lug strap with a detachable bunter which is readily detachable therefrom whereby a new bunter may be associated with the lug strap when the old one has become worn.

Other objects and advantages of the invention will become apparent during the course of the following description.

In the accompanying drawing forming a 25 part of the application and wherein like numerals are employed to designate like parts throughout the several views;—

Figure 1 is a perspective view of the invention.

Figure 2 is a perspective view of the 30 detachable bunter.

Figure 3 is a vertical section through the lug strap illustrating the bunter in position.

Figure 4 is a vertical section through the 35 lug strap.

Figure 5 is a horizontal section through the lug strap and bunter associated therewith.

Figure 6 is a fragmentary horizontal section 40 through a modified form of bunter, and

Figure 7 is a fragmentary transverse section through the same.

Referring to the drawings, wherein is 45 illustrated a preferred embodiment of the invention, the numeral 1 designates my improved lug strap which consists of a pair of spaced arms 2 joined at one end by a rear wall 3 having its inner face concaved as most clearly shown in Fig. 3. Intermediate the 50 top and bottom edges of this rear wall and in the concaved inner face is provided a horizontally disposed groove 4, the ends of which are spaced from the sides of the lug strap. In the inner face of each arm 2, at a substantial 55 distance from the rear wall 3, I provide a vertically disposed groove 5.

As the lug strap is constructed from wood, fiber or and other suitable material, the arms thereof may flex to a certain extent to accommodate therebetween a bunter 60 designated by the numeral 6. This bunter is formed from leather, fiber or the like and assumes the form of a block having outwardly convexed ends 7, one of which is adapted to closely engage the inner face 65 of the rear wall 3 and is provided with an outwardly extending rib 8. This rib is of substantially the same dimensions as the groove 4 to fit therein when the bunter assumes its proper relation with the lug strap. 70 Each side 9 of the bunter is equipped intermediate its ends with a vertically disposed rib 10 for reception in the grooves 5 provided in the arms of the lug strap. An outwardly extending shoulder 11 is provided 75 upon the bunter at the top and bottom of each side 9 for the purpose of engaging over the longitudinal edges of the lug strap arms 2. It is of course, obvious that these shoulders may be formed integral with the 80 bunter as shown in Fig. 2, or may be secured to the bunter by means of rivets 12 as shown in Fig. 7.

The ribs 8 and 10 may also be formed as 85 integral parts of the bunter or may be of a detachable nature. In the latter instance, the ends of the ribs are extended inwardly and embedded in the bunter.

From the foregoing description it will 90 be apparent that in order to assemble the bunter with the lug strap it is necessary to slightly force the arms of the latter outwardly sufficiently to accommodate and engage opposite sides 9 of the bunter. It is then forced in between the arms 2 toward 95 the rear end of the lug strap until the horizontal rib 8 is received in the horizontal groove 4, the rear convex end 7 of the bunter engages the concaved inner surface of the rear wall 3 and the vertical ribs 10 are seated in their 100 respective grooves 5 in the arms 2. As the shoulders 11 engage and ride upon the longitudinal edges of the lug strap arms, vertical movement of the bunter is precluded. As the rib 8 engages the horizontal groove 4 in the rear wall, the bunter is also prevented from vertical movement. Longitudinal movement of the bunter with respect to the arms of the lug strap is prevented by the vertical ribs 10 engaging the grooves 5 110 in the arms of the lug strap. When it is desired to remove the bunter after it has

become damaged or worn from contact with the picker stick not shown, the arms of the lug strap are slightly separated sufficiently to permit the bunter being moved outwardly 5 toward the free end of the arms 2. It is of course obvious that the lug strap may be connected with the sweep stick, not shown, in any desired manner.

The foregoing description and accompanying 10 drawings have reference to what might be considered to be the approved or preferred form of my invention. I desire it to be understood that I may make such changes in the construction, 15 combination and arrangement of parts, materials, dimensions, et cetera, as may prove expedient and fall within the scope of the appended claims.

Having thus fully described my invention 20 what I claim as new and desire to secure by Letters Patent, is:—

1. The combination with a lug strap having depressions therein, of a detachable bunter, connected therewith and projections 25 on said bunter to fit said depressions.

2. The combination with a lug strap having grooves extending angularly relative to

each other, of a detachable bunter, and ribs on said bunter to fit said grooves to prevent accidental dislodgement of the 30 bunter.

3. The combination with a lug strap having a horizontal groove in its end, and a vertical groove in each side, of a detachable bunter having shoulders for engagement 35 with the edges of the lug strap, and said bunter having ribs to fit said grooves for the purpose set forth.

4. The combination with a lug strap, of a dependable bunter, said bunter having a 40 pair of spaced shoulders projecting laterally from each side thereof, each pair of shoulders being adapted to overlap and removably engage the upper and lower longitudinal edges of said strap, and means for 45 preventing relative movement between the bunter and lug strap.

In testimony whereof I affix my signature in presence of two witnesses.

ROBERT THOMAS POWERS.
